UNITED STATES PATENT OFFICE

ANTHON G. JOHNSON, OF GILMAN, IOWA

METHOD OF PERMANENTLY WAVING HAIR

Application filed February 4, 1931. Serial No. 513,848.

This invention relates to the so-called "permanent waving" of hair and has for its principal object the successful waving of the hair without the possibility of harm to the hair, patient or operator.

A further object of my invention is to provide a non-electric method or process of permanently waving hair that is not painful to the patient during the permanent waving of her or his hair.

A still further object of this invention is to provide a means whereby an excellent permanent wave may be given and obtained in out-of-the-way places where suitable electrical current is not available.

A still further object of my invention is to provide a method of permanently waving live hair that is exceptionally beneficial to the hair so waved.

A still further object of this invention is to provide a method of permanently waving hair that may be used successfully by individuals not particularly skilled in the art of permanently waving hair.

These and other objects will be apparent to those skilled in the art.

My invention consists in the method or process hereinafter set forth, pointed out in my claims and illustrated in the accompanying drawings, in which:

Fig. 1 is an end view of the shelled pad resting in an absorbing hot oil from a receptacle.

Fig. 2 is a top plan view of the shell embraced pad in an open condition.

Fig. 3 is a plan view of the usual spool upon which the hair to be permanently waved is wound.

Fig. 4 is an end view of the shell embraced pad clamped around the spool holding the hair to be waved.

The present method of permanently waving hair is to subject the hair wound on the spool to intense electric heat. This method is very objectionable because of possible electrical shorts taking place in the complicated electrical heating mechanism, which may not only damage the hair but electrocute the patient and possibly the operator. Furthermore, such heat obtained from electricity is

not always easily controlled in tensity to meet the varying requirements and it is a very common experience to not only seriously burn the hair of the patient, but to burn the scalp of the patient. It is for these reasons that many individuals hesitate to have their hair permanently waved, but by the use of my method of permanently waving hair such objections are completely overcome, as will hereinafter be appreciated.

My method or process of permanently waving hair consists chiefly in using extremely hot oil for the hair heating means as distinguished from dangerous electrical heat. Any suitable oil beneficial and not harmful to the hair may be used.

This oil may be brought to a high temperature wherever any type of heat or fire is available. In the drawings I show a receptacle 10 having therein oil 11. As an illustration this receptacle may be placed on a stove or over a suitable lamp in order to bring the oil 11 to a high temperature. The oil conveying means is in the form of a controllable pad and consists of two rigid shell members 12 and 13 hinged together and embracing the upper side of an absorbent member 14, as is shown in the drawings. This member 14 may be of any suitable material such as felt, layers of cloth, or the like to form a suitable pad. The numeral 16 designates the usual spool having the hinged hair clamping member 17 and upon which the hair 15 is tightly wound, as is well known in the art. After a lock of hair has been tightly wound around the spool and clamping member 17, the pad assembly is placed around the same, as shown in Fig. 4, and is tightly held in place by a yieldable spring member 18, which engages the sides of the two hinged shells 12 and 13. By the shells 12 and 13 each being of curved construction, as shown in the drawings, the pad 14 will completely embrace the spool and hair wound thereon. The oil in the pad 14 which is of great temperature will highly heat the hair coiled around the spool, thereby permanently waving the hair in the usual manner as heat is applied to it in a stretched coiled condition. As soon as the pad 14 becomes cooled and the

coil of hair has been subjected to the heat from the pad, the member 18 may be removed and the pad assembly removed from the spool.

5 Any number of spools and pad assemblies may be used in the process of permanently waving a head of hair, or if it is desired, the hair may be waved by the treating of a strand at a time. After the entire head of hair has been curled by my invention, the hair is submitted to the usual strengthening solution.

10 After the strengthening solution has properly penetrated in the hair, it is shampooed and rinsed in the usual manner, after which it is ready for the setting of the wave and then dried.

15 By the foregoing disclosed method of permanently waving hair it will be noted that there is no possibility of burning or seriously scorching the hair and that electrical shocks and burns are completely eliminated as no electricity is employed in the process. This assured safety to the hair, patient and operator causes individuals wishing to have permanent waves to proceed to have such waves without hesitancy over the outcome.

20 Another important feature of my method of permanently waving hair is the economy in which a head of hair may be permanently waved. The parts needed are few and the cost of heating the oil is negligible. As is well known electric permanent waving machines are very costly indeed.

25 I claim as my invention:

1. The method of permanently waving hair consisting in stretching and coiling the hair, applying hot previously heated oil to said stretched and coiled hair, washing the hair free of said oil, and last wave setting said hair.

10 2. The method of permanently waving hair consisting in coiling the hair, applying hot previously heated oil to said coiled hair, washing the hair free of said oil, and last wave setting said hair.

15 3. The method of permanently waving hair consisting in coiling and stretching the hair around a rigid member, applying hot previously heated oil to said stretched and coiled hair, washing the hair free of said oil, and last wave setting said hair.

20 4. The method of permanently waving hair consisting in stretching and coiling the hair around a rigid member, embracing the stretched and coiled hair and rigid member with a saturated pad of hot previously heated oil, removing the pad after it is cooled, and then shampooing the hair.

25 5. The method of permanently waving hair consisting in stretching and coiling the hair around a rigid member, embracing the stretched and coiled hair and rigid member with a saturated pad of hot previously heated oil, removing the pad after it is cooled,

uncoiling the hair from said rigid member, subjecting the hair to a strengthening solution, next shampooing the hair, and lastly wave setting the hair.

6. The method of permanently waving hair consisting in wrapping and stretching the hair around a rigid member, heating oil to a high temperature, absorbing said heated oil in a pad, the placing of said heated pad with said heated oil around the hair on said rigid member, the removal of said pad after it has heated said hair, the unwinding of said hair from said rigid member, the applying of a strengthening solution to said hair, the shampooing of said hair, and lastly the wave setting of said hair.
